METAL FORMING MACHINE

Albert Rafter, Glen Ridge, N. J., assignor to
Rafter Machine Company, Belleville, N. J., a
partnership composed of Albert Rafter and
John C. Rafter, Jr.

Application December 14, 1932, Serial No. 647,121

4 Claims. (Cl. 153—3)

This invention relates to machines for forming cold metal into desired shapes, and more particularly to improvements in the means for driving such machines.

5 Metal forming machines of the type herein considered generally include a plurality of units, each of which has an upper and a lower spindle and die rolls fixed to said spindles. Heretofore, it has been the practice to provide a gear system 10 to drive each unit, thus materially increasing the cost of such machines. It has been proposed to dispense with the driving gear systems by providing worms mounted on a shaft transverse to the spindles, but the use of a worm and worm wheel arrangement has heretofore been objectionable as the tremendous force necessary to be applied to the worm places unusual stresses and strains on the worms, and they tend to grind themselves to pieces; also there is a constant tendency of the 15 worm to become disengaged from the worm wheel resulting from the unbalanced forces on the worm, due to the exerting of all of the forces on one side of the worm.

It is, therefore, an object of this invention to 20 provide a metal forming machine having a worm and worm wheel drive, the worm engaging two worm wheels on opposite sides thereof, so that the applied force is divided between the worm wheels, and there is no unbalanced condition of the worm; and the stresses and strains on the worm are 25 minimized.

A further object is the provision of a device for 30 driving die roll spindles of a metal forming machine, which enables ready and easy adjustment 35 of the spindles to accommodate die rolls of different shapes and different thicknesses of metal without affecting the operation of the driving device.

40 A further object is the provision in a metal forming machine of a worm and worm wheel drive, and of means for enabling the speed of the worm to be conveniently adjusted to the speed which causes the most efficient operation of the worm.

45 These and other advantageous objects which will later appear, are accomplished by the simple and practical construction and arrangement of parts hereinafter described and exhibited in the 50 accompanying drawings, forming part hereof, and in which:

Fig. 1 is a plan view of a die roll unit of a metal forming machine embodying my invention.

55 Fig. 2 is a sectional view taken on line 2—2 of Fig. 1.

Fig. 3 is a sectional view taken on line 3—3 of Fig. 1, and

Fig. 4 is a sectional view taken on line 4—4 of Fig. 1.

Referring to the drawings, a die roll unit is shown to comprise a forward support 5, a middle support 6, and a rear support 7; and journaled in said supports are a pair of spaced upper spindles 8 and 9 and a pair of spaced lower spindles 10 and 11. The spindles 9 and 11 carry die rolls 12 and 13 designed to give a metal sheet a predetermined shape and spindles 8 and 10 carry die rolls 14, 15 respectively to further shape the metal sheet designated by the numeral 16 in Fig. 3.

Fixed to the upper spindles 8 and 9, respectively, are gears 17 and 18 which may or may not be of the same diameter. Gears 17 and 18 are in mesh with a pinion 19 mounted upon an upper shaft 20 journaled in the supports 6 and 7 and positioned between the spindles 8 and 9. Similarly fixed to lower spindles 10 and 11, respectively, are gears 21 and 22 which are in mesh with a pinion 23 fixed to a shaft 24 journaled in the supports 6 and 7 and positioned between the spindles 10 and 11. Fixed to the upper spindle 20 is a worm wheel 25 which is in mesh with a worm 26, positioned below the worm wheel 25, and the worm 26 is also in mesh with a worm wheel 27 positioned below the worm 26 and fixed to the shaft 24.

The worm 26 is fixed to a shaft 28 extending at right angles to the spindles and shafts above mentioned, said shaft 28 being supported by bearings 29 mounted upon the rear support 7.

As shown in the drawings, a die roll unit embodying my invention comprises substantially the structure above described, and such a unit can be readily connected to other similar units by coupling the shafts 28 of adjacent units by means of splines 30 as shown in Fig. 1.

In many instances, metal forming machines include a large number of units as above described, and the expedient of connecting the several units by coupling the shaft 28 enables the ready insertion or removal of a unit with very little effort. The shaft 28 is driven by any suitable means, and the shaft, as is seen from the drawings, lies between the supports 6 and 7, thus presenting a desirable simplified structure with no parts being exposed.

Now, as is well known, a worm in engagement with a worm wheel has a constant tendency to disengage itself and to grind itself to pieces. For efficient operation of a worm and worm wheel it is accordingly essential that the threads on

the worm and worm wheel be cut at the proper angle, and that they be driven at a definite predetermined speed.

By providing a worm wheel 25 engaging the upper surface of the worm 26 and a worm wheel 27 engaging the lower surface of the worm 26, I equally distribute the power delivered by the worm, and consequently the actions of the two worm wheels 25 and 27 are balanced, thus preventing any tendency of the worm to become disengaged or to grind itself, minimizing the stresses and strains on the worm.

The upper spindles 8 and 9 are adjustable as is described in U. S. Letters Patent No. 1,792,122 granted to me on February 10, 1931, for the purpose of accommodating die rolls of different shapes and different thicknesses of metal, it being found that an adjustment of two inches is sufficient to accommodate practically all situations. Such an adjustment may be readily made in the unit above described without disengaging the gears 17 and 18 from the pinion 19.

Inasmuch as the proper speed of the gears and of the worm and worm wheels is essential to efficient operation of the worm and worm wheels, I can readily adjust the speed by removing a tooth or adding a tooth to the pinions 19 or to the gears 17 or 18, without affecting their operation.

From the above description it will be seen that I have provided a structure which enables me to easily and conveniently adjust the speed of the gearing to the speed which produces the most efficient operation of the worm and worm wheels, and enables the threads on the worm and worm wheels to be cut to a standard angle so that after they have been installed in a unit, the speed can be adjusted to give the most efficient operation. By providing a worm of a standard size and shape, I am able to economically use very durable hardened and ground worms, preferably made of steel; and the worm wheels are preferably made of aluminum bronze or the like.

It will be noted that the worm wheels are not on the spindles which carry gears 17 and 18, so that any adjustment of said spindles or the gears will not affect the operation of the worm wheels.

The foregoing disclosure is to be regarded as descriptive and illustrative only, and not as restrictive or limitative of the invention, of which obviously an embodiment may be constructed including many modifications, without departing from the general scope herein indicated and denoted in the appended claims.

Having thus described my invention, what I claim as new and desire to secure by Letters Patent, is:

60

135

65

140

70

145

75

150

1. In a metal forming machine, a front support and a rear support, an upper spindle and a lower spindle rotatably mounted in said supports, metal forming die rolls mounted on said spindles, gears fixed to said spindles, an upper shaft and a lower shaft rotatably mounted in said supports, pinions on said shafts engaging said gears, worm wheels fixed to said shafts, and a driving worm having opposite sides thereof in engagement with said worm wheels.

2. In a metal forming machine, a front support and a rear support, a pair of spaced upper spindles rotatably mounted in said supports, a pair of spaced lower spindles rotatably mounted in said supports, metal forming die rolls mounted on said spindles, each of said spindles having a gear fixed thereto, an upper shaft rotatably mounted in the supports between the upper spindles, a pinion on said shaft engaging the gears on said upper spindles, a lower shaft rotatably mounted on said supports and having a pinion fixed thereto engaging the gears on the lower spindles, a worm extending transversely to said shaft, a worm wheel on the upper shaft engaging the upper side of said worm, and a worm wheel on the lower shaft engaging the lower side of said worm.

3. In a metal forming machine, a front support and a rear support, a pair of spaced upper spindles rotatably mounted in said supports, a pair of spaced lower spindles rotatably mounted in said supports, metal forming die rolls mounted on said spindles, an upper shaft and lower shaft rotatably mounted in said supports, a worm wheel fixed to the upper shaft and a worm wheel fixed to the lower shaft, a driving worm having opposite sides thereof in engagement with said worm wheels, means on the upper shaft to drive the upper spindle, and means on the lower shaft to drive the lower spindle.

4. In a metal forming machine, a front support and a rear support, a pair of spaced upper spindles rotatably mounted in said supports, a pair of spaced lower spindles rotatably mounted in said supports, die rolls mounted on said spindles, an upper shaft rotatably mounted in the supports between the upper spindles, a lower shaft rotatably mounted in the supports between the lower spindles, gears fixed to said spindles, a pinion on the upper shaft engaging the gears on the upper spindles, a pinion on the lower shaft engaging the gears on the lower spindles, and means to drive said shafts.
